UNITED STATES PATENT OFFICE.

EMERY M. HAMILTON, OF NEW YORK, N. Y.

TYPE-WRITING MACHINE.

SPECIFICATION forming part of Letters Patent No. 430,776, dated June 24, 1890.

Application filed February 10, 1890. Serial No. 339,771. (No model.)

To all whom it may concern:

Be it known that I, EMERY M. HAMILTON, of the city, county, and State of New York, a citizen of the United States, have invented 5 certain new and useful Improvements in Type-Writing Machines, of which the following is a full, clear, and exact description, reference being had to the accompanying drawings, forming part of this specification.

10 My invention relates to a type-writing machine of the class commonly known as "type-bar" machines, in which the printing-type is carried by a vibratory type-bar, and in which the type-bars are arranged radially in a circular series and have a common printing-point at the center of the series, and also in which the type-bars are operated by key-levers arranged in a series in the machine, usually in a plane below that of the type-bar 15 circle and substantially parallel therewith, and severally connected to the respective type-bars by links or rods, whereby the series of key-levers occupies an area in the machine which is greater than that of the type-bar circle and extends laterally in the machine, so that some of the key-levers lie beyond the circumference of the type-bar circle on opposite sides thereof.

15 The principal object of my invention is to reduce the distance necessary, as above set forth, in machines of the class stated, between the type-bar circle and the series of key-levers, and thus to lessen the height or equivalent dimension of the machine, and, furthermore, 20 to permit the type-bar circle to be contracted 25 in its circumference or area, thus promoting compactness of structure.

My invention consists, primarily, in the combination, in a type-writing machine having 30 a circular series of radially-arranged vibratory type-bars and a series of key-levers fulcrumed at one side, and preferably at the rear, of said circular type-bar series, of an auxiliary lever fulcrumed outside of the circular type-bar series and intersecting and at such intersection pivotally connected to certain of the key-levers, and a link or rod connecting said auxiliary lever to certain of the type-bars in the segment of the circular series 35 thereof which is adjacent to the key-lever fulcrums, whereby said link or rod connecting the auxiliary lever to its said certain

type-bar may be arranged relatively to said auxiliary lever substantially at right angles thereto, as and for the purpose hereinafter set forth; and my invention also comprises the combination, in a type-writing machine, of devices, hereinafter particularly described, by which movement or feed is imparted to the spools or bobbins of the inking-ribbon. 60

In the drawings, Figure 1 is a plan of a type-writing machine containing my invention. Fig. 2 is a similar view of the same, the paper-carriage and top plate of the machine being removed and a portion of the type-bar ring cut away to disclose the key-levers, auxiliary levers, and connecting-links arranged according to my invention. Fig. 3 is a vertical section of the machine, taken on line *x x*, Fig. 1, looking toward the rearward end of the machine, the paper-carriage and type-bars being removed, and showing a single key-lever and auxiliary lever. Fig. 4 is a vertical section of the machine, taken on line *y y*, Fig. 1, and at right angles to the section shown in Fig. 3, and showing two type-bars and a portion of the key-levers and auxiliary levers. Fig. 5 is a plan in detail illustrating two trains of levers and their type-bars, one of said trains including an auxiliary lever; and Fig. 6 is a vertical section in detail on line *z z*, Fig. 5, illustrating said two lever-trains and the type-bars actuated thereby.

In Figs. 1, 3, and 4 the devices constituting the inking-ribbon movement are illustrated.

The machine shown in the drawings comprises certain novel devices by means of which the type-bars are pivoted and supported in their series, the paper-carriage is moved, the platen carried by the carriage is given the usual motions and holds the paper for printing, and the spacing-key is mounted and arranged. A description of these several novel devices is not necessary herein, as they constitute no part of the invention covered thereby; but they are reserved herefrom and made the subject-matter of other several applications for Letters Patent by me, to wit: Serial No. 339,766, relating to the type-bar fulcrums; Serial No. 339,767, relating to the paper-carriage, and Serial No. 339,770, relating to the spacing-key, filed simultaneously

herewith, and Serial No. 343,108, relating to the support and arrangement of the type-bars in their series, filed March 8, 1890.

At A is represented a series of type-bars arranged radially in a circle and fulcrumed to brackets in a holding-ring A'. The type-bars are all usually fulcrumed in the same plane and strike or print at a common printing-point, which is at the center of the type-bar circle.

At B is represented a series of key-levers, usually and preferably arranged in the machine, as shown, below and in a plane parallel to the plane of the type-bar circle, so as to extend laterally horizontally of the machine. The key-levers are pivoted or fulcrumed in the machine at or beyond one of the sides of the type-bar circle, and preferably to the rearward side thereof, and extend forwardly below the said circle to the front of the machine, where they are severally provided with finger-keys B', constituting the customary key-board. The key-levers may be fulcrumed on any of the four sides of the type-bar circle without variation from the essential features of my invention. In arranging these key-levers I find it desirable to assemble the rearward or fulcrum ends closely together, as shown in Fig. 2, and to fulcrum them all on a single bar B², carried by brackets B³, secured to and depending from a top plate B⁴, upon which plate the various parts of the machine are mounted, as hereinafter set forth. A shoulder b² is preferably provided on the end of each lever at its under edge, as shown, adapted to seat to the under face of the fulcrum-bar B², as shown in Fig. 4, and a spring b³, seated by an angularly-bent end or heel, as shown, in the bar B², may extend thence to and beneath each of the key-levers and be furnished with an angular bifurcated opposite end or projection b⁴, adapted to engage the under edge of the lever. This fulcrum mounting of the key-levers is structurally economical, and possesses simplicity, effectiveness, and durability, the arrangement of the shoulder b² on the lower edge of each lever, by which the levers are seated to the bar B², adapting the levers formed of flat metal strips or bars to the strain thereon when they are moved or vibrated on their respective fulcrums, and gives the described levers an increased rigidity during vibration. The assembling of the levers is likewise simplified by the described arrangement, as they may be readily seated to the bar B², and the springs b³ quickly engaged by slightly flexing them and springing the end b⁴ of each over the edge of its respective lever. In moving the levers they vibrate against the stress of the springs respectively in operating the type-bars, and upon being released are returned to their normal positions by the recoil of the springs respectively.

From their closely-assembled fulcrums, as described, the key-levers extend forward in

the machine divergently, respectively, to each other. By this means the forward ends of the levers are given a separation relatively to each other at their forward or key ends to accommodate the attached finger-keys at the key-board, as shown.

Referring now to Figs. 2, 3, 4, 5, and 6, illustrating plainly the primary feature of my invention, b represents one of those key-levers B which lie or pass within the line of the circumference of the type-bar circle, and b' represents one of those key-levers B which lie or pass beyond the edge of such circle. In carrying out the primary feature of my invention I employ an auxiliary lever C, fulcrumed or pivoted outside of the type-bar circle and preferably, as shown, at one end to a bracket B⁵, which is desirably secured to and depends from the top plate B⁴, so that said auxiliary lever will extend laterally of the machine and to and across and preferably above the key-lever b', to which it is pivotally connected at its intersection therewith, desirably by a link c. The auxiliary lever C extends to a point in line directly below a type-bar in the segment of the circular series thereof which is adjacent to the key-lever fulcrums, and is there pivotally connected to said type-bar by a link or rod D, which link or rod may be arranged relatively to said auxiliary lever substantially at right angles thereto, as shown. It is obvious that I am enabled by means of these described devices to construct a machine in which the type-bar circle may be made of such diameter only as will accommodate the fulcrums or journal-bearings of the type-bars, with the radial type-bars themselves of such a length only as will enable them to strike at a common printing-point at the center of the circle, and that the key-levers may be arranged or located immediately below and close to the pendent ends of the type-bars when the latter are in a position of rest, and that by an auxiliary lever C, pivotally connected to certain of the key-levers b', lying beyond the circumference of the contracted type-bar circle, and a link D, arranged at right angles to said auxiliary lever, as described, and connecting the same to a type-bar in the rear segment of the circular type-bar series, I may, by a depression of the key-lever b' at its finger-key, obtain the sum of the vibrations of the said key-lever and auxiliary lever in a direct vertical pull through the link D on the type-bar, so that while structural compactness in the machine is promoted the actuating-lever movement is communicated to the type-bar from a lever lying beyond the type-bar circle in the most effective manner.

It is apparent that in a machine thus constructed a key-lever b passing under the type-bar circle may be connected directly to a type-bar in the front segment of the circular type-bar series, in line with it above it, by a link D', arranged at right angles to the key-lever, as shown in Figs. 4, 5, and 6, and it is

also evident that an auxiliary lever C may be so proportioned and arranged to intersect and be pivotally connected to a key-lever b' lying beyond the type-bar circle at such a point 5 relatively to the fulcrums of each of said levers that the sum of the length of the auxiliary lever from its fulcrum to its joint with the link D uniting it to a type-bar in the rear segment of the circular type-bar series 10 and of the key-lever b' from its fulcrum to its joint with the said auxiliary lever will be substantially equal to the length of the key-lever b from its fulcrum to its joint with its link D' uniting said lever b directly to a type-bar in the front segment of the circular type-bar series, whereby the sum of the vibrations 15 of the key-lever b' and its auxiliary lever, by a depression of said key-lever b' at its finger-key, will be substantially the same as the vibrations of the key-lever b by a substantially equal depression thereof at its finger-key, so that an equal movement of the key of a lever lying under the type-bar circle and of the key of a lever lying beyond such circle will 20 effect an equal extent of vibration of their respective type-bars in printing.

In constructing a type-writing machine containing my invention I employ a series of auxiliary levers C, as shown in Fig. 2, in two 25 sections or divisions corresponding to the groups of the key-levers which lie beyond the type-bar circle or opposite edges thereof. In Fig. 2 one of these sections or divisions of the series is fully shown, and it will be understood that the opposite section (partly 30 shown) is similar thereto in all respects. The auxiliary levers C of each section are desirably all pivoted or fulcrumed at one end to a common rod or pin set in a bracket B⁶, which, 35 as stated, is secured to the top plate B⁴, and depends therefrom. The said auxiliary levers are preferably severally controlled by retracting springs c', similar in form and application to the springs b³ of the key-levers, hereinafter described. These levers C extend laterally in the machine, and preferably in substantially parallel lines across and immediately above those of the key-levers—namely, 40 b'—which lie beyond the type-bar circle and 45 reach respectively to type-bars in the segment thereof which is on the side adjacent to the key-lever fulcrums—that is to say, to the segment of type-bars which is to the rearward of the machine.

The levers C preferably terminate, respectively, at points in line below their several type-bars in such segment, and they are severally pivotally connected, as by short links c, to key-levers b' at their intersection therewith, and at their ends which are opposite to their fulcrums are connected to their respective type-bars in the rear segment of the circular type-bar series by links D, which links may be arranged relatively to their respective auxiliary-levers at a right angle thereto, as shown. The key-levers b of the series thereof which pass under the type-bar circle are con-

nected, respectively, to type-bars in the segment on the front side of the machine by links D', which may be arranged at right angles to their key-levers. I find this arrangement preferable, for the reason that the length of the levers b, respectively, from their fulcrums to the type-bars in the front segment obviously adapts them to be connected to 70 their type-bars by links D' which are rectangular to the key-levers, and to thereby impart an effective movement to the type-bars through said links, while the distance between the fulcrums of the key-levers b', respectively, which lie beyond the type-bar circle, and points in line with type-bars in the rear segment thereof, being comparatively small, the auxiliary levers C can be effectively combined with such key-levers b' in not 75 only obtaining a direct vertical pull on the links D, but also in multiplying the lever movement between the finger-keys and the type-bars. In arranging the auxiliary levers C of each division of the series thereof I 80 therefore so proportion the length of each auxiliary lever and link it to a key-lever b' at such a distance from the fulcrum of its key-lever that the sum of the total length of each auxiliary lever and the length of its 85 key-lever from its fulcrum to its joint with the auxiliary lever shall be approximately 90 the same in all the key-levers and auxiliary levers of the combined series thereof, whereby substantially the same vibration or depression of all the key-levers b' at their key ends 95 will effect a substantially equal vibration of the auxiliary levers at their joints with their respective links D, and consequently a substantially equal movement of all their 100 respective type-bars in the rear segment of the type-bar circle in printing. And, furthermore, it will be understood that in thus arranging the levers b' and C the said levers are so proportioned, fulcrumed, and united to 105 each other, respectively, and to their links D, as recited, relatively to the proportions and arrangement, respectively, of the key-levers b and their links D', connected to the type-bars 110 in the front segment of the type-bar circle, as 115 hereinbefore set forth, that a substantially similar movement or depression at their finger-keys of any of the key-levers b and b' will effect a substantially similar movement of the links D or D', as the case may be, and 120 consequently a substantially like oscillation of all the type-bars of the series thereof.

By arranging the key-levers, fulcrumed as set forth, at the rear side of the type-bar circle closely adjacent to the ends of the type-bars when said type-bars are normally pendent in the machine, and by arranging the auxiliary levers fulcrumed outside of the type-bar circle immediately above the key-levers and intersecting the same, as described, I am 125 enabled to connect all the type-bars to their actuating levers by links which are substantially rectangular to said levers, and to have the links connecting the type-bars in the rear 130

segment of the type-bar circle to their respective auxiliary levers of a less length than the links connecting the type-bars in the front segment of the type-bar circle directly 5 to their respective key-levers, thereby promoting compactness of structure in the machine.

In the machine shown motion is given to the carriage-actuating mechanism by means of 10 a lever E, which is pivotally hung at e in the hangers or frame B³, Figs. 3 and 4, an arm e' of said lever reaching to and engaging the carriage-actuating mechanism, while the arm e² is engaged by all the key-levers, as by 15 means of a bar e³, linked to said arm e² and hanging below and against the under faces of the key-levers. The depression of any of the key-levers rocks the lever E, thus vibrating its arm e'. This lever is commonly called 20 the "universal lever" in type-writing machines, and its function and operation are well known.

It should be noted that in promoting structural compactness in the machine a base-plate or standard is dispensed with, and that a top plate B², with the hangers B³, carrying the bar B², and the fulcrum-brackets B⁶, secured to 25 said top plate, serve as the supporting-frame, upon which the several working parts of the 30 machine are fastened. The plate B⁴ may serve as a lid or cover to a case or box B⁷ enclosing the levers and type-bars, as shown. The type-bar ring A' may be secured to the plate B⁴, and a supplemental plate B⁸, perforated 35 to accommodate the passage and play of the finger-keys B⁹, may extend from or be secured to the forward edge of said top plate.

At F and F' are shown the inking-ribbon spools carrying the usual inking-ribbon R, 40 said spools having respectively the shafts f f', having bearings in the machine-frame, as shown. These shafts are arranged horizontally on the machine, and are provided with the ratchet-wheels f² f³, respectively.

45 G and G' are bell-crank levers fulcrumed, respectively, at g and g', with an arm g² of each pivotally connected, preferably by a pin g³, common to both said arms, to a rod g⁴, which is reciprocated by the arm e' of the 50 universal lever. Each said bell-crank lever has a pawl-like arm g⁵ arranged and located in the machine at a right angle to the plane of its respective ratchet on the spool-shafts and reaching to and adapted to engage the 55 periphery of said ratchet flatwise of said pawl-arm, as shown.

H is a bar carrying or provided with projections h, having, respectively, oppositely-inclined faces h', said projections being located 60 on said bar relatively to said pawl-arms g⁵, so that when one of said projections engages one of said pawl-arms by its inclined face the other projection is free from engagement with the other pawl-arm, as shown. The bar 65 H has longitudinal movement on suitable guides h², so that either projection may be engaged to the corresponding pawl-arm. The

pawl-arms are flexible or adapted to have play flatwise at their fulcrums, whereby when the bar H is moved to bring either one 70 of its projections into engagement with the corresponding pawl-arm, said pawl-arm will be thereby lifted out of engagement with its ratchet, the other pawl-arm being by the same movement of the bar released from the 75 other projection, and hence free to engage its ratchet. The reciprocation of the rod g⁴ operates to oscillate both the levers G and G' continuously, and the respective pawl-arms g⁵ of said levers, by engagement with the 80 ratchets f² f³ alternately, respectively, thereby operate to rotate the ribbon-spoils in either direction, as desired, at each vibration of the universal lever during the operation of printing.

The form and arrangement given to the levers G G' and their pawl-arms g⁵ and the location of the latter, as described, relatively to the inking-spool ratchet—namely, at right angles flatwise to the planes of the respective ratchets—enables the mechanism which actuates the inking-spoils to be given compactness of structure and to occupy but a 90 very limited space in the organization of the machine.

95 What I claim as my invention, and desire to secure by Letters Patent, is—

1. In a type-writing machine having a circular series of radially-arranged vibratory type-bars and a series of key-levers fulcrumed 100 at one side of the type-bar circle, the combination therewith of an auxiliary lever fulcrumed outside the type-bar circle and intersecting and at such intersection pivotally connected to certain of the series of key-levers, and a link or rod connecting said auxiliary lever to certain of the series of type-bars in the segment of the circular series thereof adjacent to the key-lever fulcrums, substantially as and for the purpose 105 set forth.

2. In a type-writing machine having a circular series of radially-arranged vibratory type-bars and a series of key-levers fulcrumed in the machine at the rear side of the type-bar circle, the combination therewith of an auxiliary lever fulcrumed outside the type-bar circle and intersecting and at such intersection pivotally connected to certain of the series of key-levers, and a link or rod connecting said auxiliary lever to certain of the series of type-bars in the rear segment of the circular series thereof in the machine, substantially as and for the purpose set forth.

3. In a type-writing machine having a circular series of radially-arranged type-bars and a series of key-levers fulcrumed at one side of said type-bar circle, the combination therewith of an auxiliary lever fulcrumed outside said type-bar circle and intersecting 120 and at such intersection pivotally connected to certain of the series of key-levers, and a link or rod rectangular to said auxiliary lever and connecting said lever to certain of the

series of type-bars in the segment of the circular series thereof adjacent to the type-bar fulcrums, substantially as and for the purpose set forth.

5 4. In a type-writing machine having a circular series of radially-arranged type-bars and a series of key-levers fulcrumed at one side of said type-bar circle, the combination therewith of a link or rod connecting certain 10 of the series of key-levers to certain of the circular series of type-bars in the segment of said series opposite to the type-bar fulcrums, and an auxiliary lever fulcrumed outside the type-bar circle and intersecting and at such 15 intersection pivotally connected to certain of the series of key-levers, together with a link or rod connecting said auxiliary lever to certain of the series of type-bars in the segment of the circular series thereof adjacent to the 20 type-bar fulcrums, substantially as and for the purpose set forth.

5 5. In a type-writing machine having a circular series of radially-arranged vibratory type-bars and a series of key-levers fulcrumed 25 at one side of the type-bar circle, the combination therewith of a series of auxiliary levers fulcrumed outside the type-bar circle and intersecting and at such intersection severally pivotally connected to key-levers of 30 the series thereof, and links or rods severally connecting the auxiliary levers respectively to type-bars in the segment of the circular series thereof adjacent to the key-lever fulcrums, substantially as and for the purpose 35 set forth.

6. In a type-writing machine having a circular series of radially-arranged vibratory type-bars fulcrumed in a plane or planes horizontal in or parallel to the base of the 40 machine, and a series of key-levers fulcrumed at one side of said type-bar circle and extending below the same in a plane substantially parallel to the plane or planes of the type-bar fulcrums, the combination therewith of a series 45 of auxiliary levers fulcrumed outside the type-bar circle and extending between and in a plane substantially parallel to the planes of the type-bar circle and key-levers and intersecting and at such intersection pivotally connected severally to certain of the key-levers, and links or rods severally connecting said auxiliary levers to certain of the type-bars in the segment of the circular series 50 thereof adjacent to the key-lever fulcrums, 55 substantially as and for the purpose set forth.

7. In a type-writing machine having a circular series of radially-arranged vibratory type-bars and a series of key-levers fulcrumed at one side of the type-bar circle, the combination therewith of a series of auxiliary levers fulcrumed outside said type-bar circle and extending in parallel lines across and at their intersection therewith pivotally connected, respectively, to key-levers of the series 60 thereof, and links or rods severally connecting said auxiliary levers to certain of the type-bars in the segment of the circular series 65 thereof, substantially as and for the purpose set forth.

ries thereof adjacent to-said key-lever fulcrums, substantially as and for the purpose set forth.

8. In a type-writing machine having a circular series of radially-arranged vibratory type-bars and a series of key-levers fulcrumed at one side of the type-bar circle, the combination therewith of links or rods connecting certain key-levers of the series thereof to certain type-bars of the said series thereof, and auxiliary levers fulcrumed outside said type-bar circle and intersecting and at such intersection severally pivotally connected to certain other key-levers of the series thereof, together with links or rods severally connecting said auxiliary levers to certain other of the type-bars of the circular series thereof, substantially as and for the purpose set forth.

9. In a type-writing machine having a circular series of radially-arranged type-bars and a series of key-levers fulcrumed on a common bar at one side of said type-bar circle, the combination therewith of a series of auxiliary levers fulcrumed on a common bar outside the type-bar circle and extending across and at their intersection therewith pivotally connected, respectively, to key-levers of the series thereof, and links or rods severally connecting said auxiliary levers to certain of the type-bars in the segment of the circular series thereof adjacent to the common fulcrum-bar of the key-levers, substantially as and for the purpose set forth.

10. In a type-writing machine having a circular series of radially-arranged type-bars and a series of key-levers fulcrumed in the machine on a common bar at the rear of said type-bar circle and extending divergently forward in the machine below said type-bar circle, the combination therewith of a series of auxiliary levers fulcrumed on a common bar outside said type-bar circle and extending across and at their intersection therewith severally pivotally connected to key-levers of the series thereof intermediate said key-lever series and said type-bar circle, and links or rods severally connecting said auxiliary levers to certain of the type-bars in the segment of the circular series thereof adjacent to the common fulcrum-bar of the key-levers, together with a universal lever located adjacent to the said fulcrum-bar of the key-levers and having an arm adapted to engage all said key-levers at a point near their fulcrums, substantially as and for the purpose set forth.

11. In a type-writing machine having a circular series of radially-arranged type-bars and a series of key-levers fulcrumed at one side of said type-bar circle, the combination therewith of a series of auxiliary levers fulcrumed outside said type-bar circle and severally intersecting and at such intersections severally pivotally connected to certain of the key-levers of the series thereof, together with links or rods severally connecting said auxiliary levers to certain of the type-bars in the segment of the circular series thereof ad-

- adjacent to said key-lever fulcrums, said certain key-levers and the auxiliary levers pivotally connected thereto being proportioned, fulcrumed, and connected severally and respectively, so that the sums of the lengths of each said certain key-levers from their respective fulcrums to their joints with their respective auxiliary levers and of the several auxiliary levers from their respective fulcrums to their joints with their respective links or rods connecting them severally to their type-bars are substantially equal throughout the series of said levers, substantially as and for the purpose set forth.
- 15 12. In a type-writing machine having a circular series of radially-arranged type-bars and a series of key-levers fulcrumed at one side of said type-bar circle, the combination therewith of links or rods severally connecting certain of said key-levers directly to certain of said type-bars, and a series of auxiliary levers fulcrumed outside said type-bar circle and intersecting and at such intersection severally pivotally connected to certain other of said key-levers, together with links or rods severally connecting said auxiliary levers to certain other of the type-bars, said certain key-levers connected directly to certain of the type-bars and said certain other key-levers and the auxiliary levers to which they are severally pivotally connected, and which auxiliary levers are severally connected to certain other of the type-bars, being proportioned, fulcrumed, and severally connected, as described, so that the sums of the respective vibrations of the auxiliary levers and those of the key-levers connected thereto will be equal, relatively to the type-bars, to the respective vibrations of those of the key-levers connected directly to type-bars, substantially as and for the purpose set forth.
- 16 13. In a type-writing machine, the combination, with a series of vibratory type-bars, of a series of key-levers for actuating said type-bars, each of said key-levers having a shoulder b^2 on the under side of the fulcrum end, a bar B^2 , common to all the key-levers, and to which they are fulcrumed by their said shoulders, and a series of springs b^3 , having each an angularly-bent heel and an angularly-bent bifurcated opposite end, by which they are severally seated in said bar and severally engage said key-levers, substantially as and for the purpose set forth.
- 17 14. In a type-writing machine, the combination, with a top plate B^4 , of brackets B^3 , pendent from said plate, a bar B^2 , carried by said brackets, and a series of key-levers B , fulcrumed on said bar, substantially as and for the purpose set forth.
- 18 15. In a type-writing machine, the combination, with a top plate B^4 , of brackets B^3 , pendent from said plate, a bar B^2 , carried by said brackets, and brackets B^6 , pendent from said plate, together with a series of key-levers B , fulcrumed on said bar B^2 , and a series of auxiliary levers C , fulcrumed on said brackets B^6 , said auxiliary levers being severally pivotally connected to key-levers of the series thereof, substantially as and for the purpose set forth.
- 19 16. In a type-writing machine, the combination, with the ink-ribbon spools $F F'$, their respective shafts $f f'$, and ratchet-wheels $f^2 f^3$ on said shafts, respectively, of bell-crank levers $G G'$, an arm g^2 of each of which is pivotally jointed to a reciprocating rod g^4 and an arm g^5 of each of which is located at right angles to the plane of and engages, respectively, the spool-ratchets, and a bar H , having longitudinal movement and provided with projections h , adapted to severally alternately engage an arm g^5 of said bell-crank levers, substantially as and for the purpose set forth.

EMERY M. HAMILTON.
